N. E. SALSICH

ROLLED STEEL GUARD RAIL

Filed July 17, 1923

UNITED STATES PATENT OFFICE.

NEIL E. SALSICH, OF BETHLEHEM, PENNSYLVANIA.

ROLLED STEEL GUARD RAIL.

Application filed July 17, 1923. Serial No. 652,039.

To all whom it may concern:

Be it known that I, NEIL E. SALSICH, a citizen of the United States, and residing at Bethlehem, Lehigh County, State of Pennsylvania, have invented certain new and useful Improvements in Rolled Steel Guard Rails, of which the following is a specification.

My invention relates to rolled steel guard rails for railway rails and it has for its object to provide apparatus of this character which shall be capable of being economically made from rolled shapes and which, when installed, shall afford a strong and durable guard rail construction.

More particularly, an object of my invention is to provide guard rails made from rolled rail sections with no or little bending at the ends in order to provide flaring wheel flange entrance spaces. If rails used for this purpose are of sufficient weight, the sections are entirely straight from end to end and parallel to the main rail, metal being removed from the ends of the guard rail in order to provide flaring wheel flange entrance spaces; however, in case the weight of rails used for this purpose is such that an undue amount of metal would be removed at the ends in order to provide wheel flange entrance spaces, the ends are bent just enough to provide for removal of metal without undue weakening.

A further object of my invention is to provide a construction of the character referred to in which a flange of the guard rail shall underlap a flange of the main rail in order to resist tilting movement of the former due to lateral thrusts.

A further object of my invention is to provide, in connection with a guard rail of the character referred to, suitable tie plates which shall pass under both rails, preferably welded to the flanges of the guard rail, and serve as a force-transmitting means between the rails to resist relative movement of one with respect to the other.

Apparatus made in accordance with my invention is illustrated in the accompanying drawings, forming a part of this application, in which:

Fig. 1 is a plan view of a part of the main rail and cross ties with the guard rail construction;

Fig. 2 is a cross section on line 2—2 of Figure 1;

Fig. 3 is a cross section on the line 3—3 of Figure 1;

Fig. 4 is a cross section on the line 4—4 of Figure 1;

Fig. 5 is a fragmentary view of a modified form of my improved guard rail construction; and

Fig. 6 is a plan view of one of the tie plates detached.

Referring now to the drawings for a better understanding of my invention, I show a guard rail 10 made from a rolled shape and arranged adjacent to a main rail 11. As shown the guard rail 10 comprises a head portion 12, a web 13, and lateral flanges 14 and 15. The main rail 11 consists of a head portion 16, a web 17, and lateral flanges 18 and 19.

The guard rail 10 has its flange 14 adjacent to the main rail depressed or rolled down, as may be seen from Figures 2, 3 and 4, so as to underlap the adjacent flange 18 of the main rail.

With the type of guard rail just referred to, a special type of connection between the rails is necessary in order to resist relative movement thereof; and this connection will now be described. For this purpose, I show tie plates 21, which are shown as being of sufficient length to span a pair of ties 22

and the upper surfaces thereof serve as supporting surfaces for the substantially coplanar bottom surfaces 23 and 24 of the guard rail 10 and the main rail 11; however, it is to be understood that a tie plate 90 might be provided for each tie, it being merely necessary to slot it where it rests on a tie to provide clearance for the underlapping flange. Each tie plate 21 is provided with spike receiving openings 25 adapted to receive spikes which cooperate with the outer flange 15 of the guard rail. At the other side, each tie plate is provided with spike receiving openings 26 of eschelon formation in order that the guard rail may be correctly positioned with respect to the main rail. When the spikes are driven, they effectively connect the rails to the plate, the latter then serving to resist any spreading tendency of the rails.

Each portion of a tie plate 21 resting on

a tie 22 is provided with a slot or opening 27, as shown in Figures 1, 3, 4 and 6, to afford clearance spaces for the underlapping flange 14. If tie plates of sufficient length to span pairs of ties are used, each plate of this character is provided with a connecting portion or neck 28, between the slots 27 and which is curved to provide clearance space for the underlapping flange. 5 As shown in Figures 3 and 4, the guard rail has welded connections at 29 between the outer flange 15 thereof and the tie plate 21 and welded connections at 30 between the edge of the depressed flange 14 and the adjacent edge of a slot 27. The welded connections are advantageous particularly in transporting and in installing the rails. Such connections serve to strengthen an installation, however, it is to be understood 10 that the welded connections may be omitted for the reason that the spikes serve to connect the rails and the tie plates. The connecting portions or necks 28 of the tie plates approximately span the space between ties 15 and they serve as force-transmitting means in order to resist relative movement of one rail with respect to the other.

It is customary to provide flaring spaces between the ends of guard rails and adjacent main rails. Accordingly, therefore, with the construction shown in Figures 1 to 4, inclusive, where the guard rail 10 comprises a straight rolled rail arranged parallel to the main rail, I show the ends tapered off, as indicated from the points 32 to 33. Preferably metal is removed at the ends so as to provide faces 34 which are inclined both with respect to the longitudinal and vertical axes of the guard rail. 15 The removal of metal to provide flaring wheel flange entrance spaces at the ends of the guard rail 10 with the faces 34 inclined away from the main rail and with respect to the vertical brings into play the maximum effect to constrain wheel flanges to move toward the head of the main rail, the divergency with respect to the longitudinal axis of the main rail serving to guide wheel flanges toward the head of the main rail and the inclination of the face 34 downwardly toward the main rail, serving to utilize the force of gravity at least to some extent in order to guide wheel flanges toward the head of the main rail.

55 In case the guard rail is made of such light weight as to result in undue removal of metal or weakening at the ends, if the guard rails are made of straight sections as indicated in Figure 1, then as much metal is removed from the ends of the guard rail 10' as is advisable, the removal being indicated from the points 36 to 37 in Fig. 5, after which the portions are bent as indicated at 35. In this way, sufficient flaring 60 wheel flange entrance spaces, extending

from the points 36 to the bends 35, the outer portions between the bends 35 and the ends serving as reinforcements, may be provided. Metal is removed from the ends of the guard rail 10' in the same manner referred to in connection with Figure 1. With guard rails of light weight, therefore, the flaring spaces at the ends are provided by removal of metal as far as expedient and then by bending as far as necessary to provide adequate flaring wheel flange entrance spaces. 70 75

A foot guard 38 of uniform cross section is riveted or welded to the web portion 13 of the guard rail and it includes a flange 39 extending horizontally to a longitudinal line below the head portion 16 of the main rail and between it and the flange 18. It is preferably formed of a standard angle bar shape cut to length. The vertical flange 40 of the foot guard fits the side of the web 13 of the guard rail and this foot guard preferably extends throughout the full length of the guard rail. It serves to prevent the collection of masses of snow and ice 80 85 between the rails and makes it easy to remove such as may collect on it. At each end of the guard rail the horizontal flange 39 of the foot guard is bent downward as indicated at 42 in Figures 2, 3 and 4 and is at right angles to the top of the guard and its lower edge is so cut as to provide inclined edges 43 corresponding in inclination to the top surface of the flange 18 of the rail. The edges 43 are sufficiently close to the flange 18 to resist outward tilting movement of the main rail 11. The foot guard construction will not be more particularly referred to, as it is disclosed and claimed in my application Serial No. 652,040, filed July 17, 100 105 1923.

From the foregoing it will be apparent that I have provided a guard rail which may be made from rolled rails; it being unnecessary to bend the ends of the rail in order to provide flaring wheel flange entrance spaces if the weight of rail is sufficient; and, in case the weight of rails used for this purpose is insufficient to provide adequate material at the ends after metal is removed, then as much metal is removed as is advisable after which the end portions are bent. It will also be apparent that I have provided a special and peculiarly co-operative type of tie plate for the special form of guard rail herein disclosed and having a flange underlapping a flange of the main rail. 110 115 120

While I have shown my invention in two forms, it will be obvious to those skilled in the art that it is not so limited, but is susceptible of various other changes and modifications without departing from the spirit thereof, and I desire, therefore, that only such limitations shall be placed thereupon 125 130

as are imposed by the prior art or as are specifically set forth in the appended claims.

Having thus described the invention what is claimed as new and desired to be secured by Letters Patent is:

1. The combination with a main rail, of a rolled guard rail of approximately the same height as the main rail and tie plates connected to the guard rail for supporting both rails, the main rail flange overlapping the guard rail flange and their edges being parallel throughout the entire length of the guard rail and the guard line face of the head of the guard rail being oblique to the main rail in a longitudinal direction for a short distance from each end of the guard rail forming flaring end portions of the space between said rails for the flanges of the wheels. 70
2. The combination with a main rail, of a rolled guard rail of approximately the same height as the main rail and tie plates connected to the guard rail for supporting both rails and each extending across two adjacent ties, the main rail flange overlapping the guard rail flange and the guard line face of the head of the guard rail being oblique to the main rail in a longitudinal direction for a short distance from each end of the guard rail forming flaring end portions of the space between said rails for the flanges of car wheels. 80
3. The combination with a main rail, of a rolled guard rail of approximately the same height as the main rail and tie plates connected to the guard rail for supporting both rails, the main rail flange overlapping the guard rail flange, the web of the guard rail being parallel throughout its length to that of the main rail and the guard line face of the head of the guard rail being oblique to the main rail in a longitudinal direction for a short distance from each end of the guard rail forming flaring end portions of the space between said rails for the flanges of car wheels. 85
4. In a railroad structure, the combination of a main rail and a rolled guard rail of substantially the same height as the main rail, tie plates connected to the guard rail for supporting both rails on the ties the flange of the guard rail being depressed and forming a seat for the flange of the main rail, the web of the guard rail being parallel to the web of the main rail, the metal normally forming the guard line vertical face of the head of the guard rail being removed at its ends and for a short distance longitudinally therefrom, producing faces in planes at a slight angle to the normal face, resulting in flaring end portions of the passageway between said rails for the flange of a car wheel. 100
5. In a railroad structure, the combination of a main rail, a guard rail having oppositely-extending flanges, one of said flanges underlapping a flange of the main rail, a series of tie plates for supporting the guard and main rails, and each of said plates being provided with clearance space 75 for the underlapping flange of the guard rail, and welded connections between the outer edge of said underlapping flange and the tie plates.
6. In a railroad structure, the combination of a main rail, a guard rail having oppositely extending flanges, one of said flanges underlapping a flange of the main rail, a series of tie plates for supporting the guard and main rails, each of said tie plates having a clearance space extending parallel to the rails, and welded connections between the outer edge of the underlapping flange of the guard rail and similar edges 80 of the clearance spaces and between the outer edge of the other flange of said guard rail and the top surfaces of the tie plates. 85
7. In a railroad structure, the combination of a main rail, a guard rail having a flange which underlaps a flange of the main rail, and a series of tie plates for supporting the guard and main rails, each tie plate adapted to span a pair of railroad ties and being provided with a clearance space for 90 the underlapping flange and which extends 95 substantially parallel to the rails.
8. In a railroad structure, the combination of a main rail, a guard rail having a flange which underlaps a flange of the main rail, and a series of tie plates for supporting the guard and main rails, each tie plate adapted to span a pair of railroad ties and being provided with a clearance space extending substantially parallel to the rails 100 throughout the tie-engaging portions thereof for the underlapping flange, the portion of each tie plate between the ties of each pair being bent down to afford clearance for 105 the underlapping flange. 110
9. An article of manufacture comprising a tie plate for supporting main and guard rails, the tie plate having end portions for securing to railroad ties, each end portion being provided with a slot extending substantially parallel to the sides of the plate which are transverse to the ties, the material of the plate between the adjacent ends of the slots being depressed to define a clearance space in line with said slots. 115
10. The combination with a main rail, of a guard rail consisting of a rolled section and having its ends tapered to define flaring wheel-flange entrance spaces. 120
11. The combination with a main rail, of a guard rail comprising a rolled section arranged parallel to the main rail and having the ends of its head portion tapered off to define flaring wheel-flange entrance spaces. 125
12. The combination with a main rail, of 130

a guard rail comprising a rolled section having the ends of its head portion tapered off to define wheel-flange entrance spaces with respect to the main rail and having one flange underlapping a flange of the main rail and means for securing the guard rail in position with respect to the main rail.

13. The combination with a main rail, of a guard rail comprising a rolled section having the ends of its head portion tapered off to define wheel-flange entrance spaces with respect to the main rail and having one flange underlapping a flange of the main rail, tie plates extending beneath the rails, and weld connections between the edges of the guard rail flanges and the tie plates.

14. The combination with a main rail, of a guard rail comprising a rolled section having the ends of its head portion tapered off to define wheel-flange entrance spaces

with respect to the main rail and having one flange underlapping a flange of the main rail, and tie plates extending beneath the rails, each tie plate having spike-receiving openings contiguous to the edges of the outside flanges of the main and guard rails. 25

15. The combination with a main rail, of a guard rail comprising a rolled section having the ends of its head portion tapered off to define wheel-flange entrance spaces with respect to the main rail and having one flange underlapping a flange of the main rail, tie plates extending beneath the rails and having a clearance space for the underlapping flange, and weld connections between the flanges of the guard rail and the tie plates. 30 35

In testimony whereof I hereunto affix my signature this 5th day of July 1923.

NEIL E. SALSICH.
